UNITED STATES PATENT OFFICE.

ROBERTO IMPERIALI, OF NAPLES, ITALY.

FUSE FOR ARMOR-PIERCING PROJECTILES.

No. 903,980.

Specification of Letters Patent.

Patented Nov. 17, 1908.

Application filed February 16, 1907. Serial No. 357,753.

To all whom it may concern:

Be it known that I, ROBERTO IMPERIALI, a subject of the King of Italy, residing at 297 Corso Umberto, in the city of Naples, Kingdom of Italy, have invented a new and useful Improvement in Fuses for Armor-Piercing Projectiles; and I do hereby declare the following to be a full, clear, and exact description of the same.

The object of the present invention consists of a load-fuse that is a fuse carrying in itself not only the means of igniting the bursting charge, but also this charge itself. This fuse acts by the crushing of its metallic point, when the projectile strikes against the man of war or other vessel or ship and the fulminating cap lights the slow match directly and this fires the whole charge afterwards. The explosion, therefore, takes place a few moments after the shock, that is when the projectile has penetrated into the vessel.

In the accompanying drawings a loaded fuse made according to this invention is shown as an example.

Figure 1 shows a section of such a perforating projectile with the loaded fuse in the interior. Fig. 2 shows on an enlarged scale, the loaded fuse alone, and Fig. 3 shows on a still more enlarged scale the head of the fuse.

The projectile —1— as shown in Fig. 1, has an internal cavity, that is almost filled by the fuse —2—. The bottom —3— of the projectile is screwed on or else fastened in any other way after the fuse has been introduced into it. Between the walls of the grenade and the fuse —2— a small space —4— will remain free, which will permit the fuse to run forward in the shell and reach the extremity of this cavity, when the fuse stops against any obstacle, so that the live power acquired will act on the point —5— with great force. The distance —30— (Fig. 1) between the point —5— and the bottom of the inner cavity —4— is determined in relation to the thickness of the armor and to the piercing capacity of the projectile —1— so that the explosion may take place, when the projectile has entirely penetrated into the vessel. The fuse (Figs. 2 and 3) consists of an external shell —6— closed at the bottom by the lid —7— which is screwed on. In its center it has an annular cavity that surrounds the tube —8—, this is soldered to the shell —6— and has a common axis with it. In this tube —8— a

cylinder —9— is placed and screwed fast: It has fixed ends —10— and —11—. The central space —12— and the annular cavity —13— are filled with gun cotton or any other powerful explosive material.

The head —11— of the cylinder —9— has a central hole with a flange —14—: This is furnished with a screw thread in which the sleeve —15— is screwed and it bears with its flange —16— on the head —11—. In this sleeve the ignition tube —17— is adapted and it fits exactly with the conical surface —18—. This tube carries the slow match —19— consisting of a suitable slow burning powder and this tube is furnished also with a fulminating cap —20—. Around the head of the tube and the sleeve —15— is placed the ring —21— which is screwed to the latter and has a central tube —22— in which the striker or percussion bolt —23— can slide. This percussion or striking bolt has a tail end —24— furnished with a screw thread and a flange —25—. A ring —26— is screwed on the tube —22— and is provided with a border —27— against which the flange —25— of the percussion bolt —23— is resting. Between the flange —25— indicated and the superior face of the tube —22— there is the space —28— in which the percussion bolt may slide freely, but this movement cannot take place on account of the small cap —29—, the internal cavity of which has a small female screw engaging or acting on the screw of the tail end —24—, so as to pull up the percussion bolt —23— and prevent its contact with the fulminating cap —20—, from which it will remain distant a few millimeters. The load fuse may be prepared completely in all its different parts except the cylinder —9—, which will be introduced into the tube —8— only at the moment when the projectile is to be used: This cylinder guided by the tube —8— is screwed to sleeve —15— at the upper extremity and to tube —8— at the lower extremity. The explosive material contained in the space —12— will be slightly compressed and moved aside by the tube —17— which, being small, will not prevent the cylinder from being introduced.

When the projectile is thrown forth from the gun, the charge of the latter communicates the initial motion to the internal surface of the projectile: Therefore the fuse will be held back by the force of inertia and remain against the bottom of the projectile.

When the projectile hits a resistant obstacle the motion of the outer shell is checked but the inner shell continues to move until it hits the inner wall of the projectile point 5 and as the small pointed cap-shaped cover —29— and the ring —26— are made of ductile metal, the violent shock will produce the complete crushing of these parts, the percussion bolt will encounter the fulminating 10 cap and the match —19— will be ignited and this being of slow combustion, the charge or load will explode somewhat after the shock and thus give the projectile the necessary time to penetrate inside the vessel that 15 has been struck.

The fuse described possesses the advantage of perfect security because that part of the charge, that must be in direct communication with the ignition tube, is screwed in 20 its place only at the moment when the projectile is to be used. As already stated besides this the percussion bolt can only be put into action by a violent shock, so that in this respect also there is a new element of 25 security.

Having now particularly described and ascertained the nature of my said invention and in what manner the same is to be performed, I declare that what I claim is:

1. In a projectile, an outer shell, an inner shell movably arranged within the outer shell and having its head spaced from the inner wall of the head of the outer shell, a charge in said inner shell, a cap of ductile 30 material arranged on the head of the inner shell and adapted to be crushed on impact

by hitting the inner wall of the head of the outer shell, and an axially movable percussion bolt normally held in inactive position by said cap, whereby, when the cap is 35 crushed on impact, the percussion bolt is free to move relatively to the charge to cause explosion of the charge.

2. In a projectile, a shell, an explosive charge in said shell, a tube containing a 40 slow burning charge adjacent to the explosive charge, a fulminating cap for said slow burning charge, a movable percussion bolt, and a cap of ductile material forming the point of the projectile and engaging said 45 bolt to normally hold the bolt from engagement with the fulminating cap and adapted to be crushed on impact to permit the bolt to strike the fulminating cap.

3. In a projectile, a shell, an explosive 50 charge in said shell, a central tube removably fitted in the shell and extending substantially throughout the length of the shell, an explosive charge in said tube separate from said first-named charge, a second tube 55 arranged in the head of the shell and projecting into said first-named tube, a slow burning charge in said second tube, and means for igniting said slow burning charge on impact. 60

In witness whereof, said ROBERTO IMPERIALI has signed this specification.

ROBERTO IMPERIALI.

In the presence of—
HOMER M. BYINGTON,
Q. DEL ZENEDELLI.
